MECHANICAL PENCIL

Robert J. Lynn, Chicago, Ill.

Application December 20, 1946, Serial No. 717,413

15 Claims. (Cl. 120—18)

1

My invention relates to a mechanical pencil having a hollow body through which a lead may from time to time be propelled into position for writing, and more particularly to the propelling unit itself and the means whereby its parts may be readily disassembled for purposes of repair, replacement or otherwise.

In a pencil of this general character, I have incorporated certain improvements which conduce to simplicity of construction, and dependability in operation. For this purpose I associate with the body of the pencil a rotatable tip which induces travel of a propeller by which an active lead is expelled through the tip end of the pencil. The construction of the tip, its connection with the pencil body, and assembly of parts which constitute the propelling unit, present certain improved features with which my invention is mainly concerned.

In the accompanying drawings are shown certain suggestive embodiments of my invention in the manner following:

Fig. 1 is a view in central longitudinal section through the pencil in its entirety;

Fig. 2 is a similar view of the propelling unit which includes an associated tip for the pencil;

Fig. 3 is a transverse section, taken on line 3—3 of Fig. 2;

Fig. 4 is a view in elevation of the propeller per se;

Figs. 5, 6, and 7 are transverse sections taken, respectively, on lines 5—5, 6—6, and 7—7 of Fig. 1;

Fig. 8, which is a view generally similar to Fig. 1, shows a modified construction of the pencil and its propelling unit;

Fig. 9 is a similar view of the propelling unit shown in Fig. 8, together with the tip associated therewith;

Fig. 10 is an elevational view of the lead guide to be used with the construction of Figs. 8 and 9;

Fig. 11 is a view in transverse section, taken on line 11—11 of Fig. 8;

Fig. 12, which is a view similar to Fig. 9, shows a modified construction of the propelling unit and of the tip associated therewith;

Fig. 13 is a transverse section, taken on line 13—13 of Fig. 12;

Fig. 14, which is a view similar to Fig. 12, shows a further modification in the construction of the propelling unit; and

Fig. 15, which is a similar view, shows the lead guide tube partially disassembled from the propelling unit of Fig. 14.

The pencil in each of the forms illustrated com-

2

prises a body A having at one end thereof a rotatable tip B forming part of a propelling unit whereby to advance an active lead l through the pencil into writing position. At the opposite body end which is open is fitted an eraser unit C which provides a closure therefor.

The body A is desirably formed of a composition material which may be molded to shape with the aid of heat and pressure. It is formed in the general shape of a barrel having inner and outer cylindrical walls 35 and 36 defining between them an annular magazine m. An end wall 37 closes the axial chamber c defined by the inner wall 35. At its opposite end the inner wall is joined to a supporting base 38 from which is axially extended a nose 40 of smaller diameter having a cylindrical section 41 beyond which the nose is tapered down at 42. Throughout the nose and base the axial chamber c is continued in the same diameter as elsewhere.

To a body A of the general kind under description is fitted the rotatable tip B which, together with the parts carried thereby, constitutes the propelling unit. As shown, this tip is of two parts, comprising an upper tapered section 45 having its walls 46 at the point of maximum diameter straightened out into cylindrical form for frictional engagement with the corresponding wall 41 of the nose. This tapered section is adapted, therefore, to be interfitted with the lower end of the body, and to be rotated relative thereto while retained frictionally in assembled relation therewith. The tip comprises also a terminal section 50, desirably of metal, which is joined to the tapered section 45 at its smaller end so as to constitute a continuation thereof. At its extremity, the terminal section is slit longitudinally at a plurality of places 51 to provide segmental spring jaws with capacity for gripping between them the lead l which is to be advanced longitudinally therethrough.

Both sections of the tip are formed interiorly with an axial passageway having a diameter slightly smaller than that of the axial chamber c within the inner walls 35 of the body. Into this passageway is inserted a coupling in the form of a tube 55 having near its lower end a slightly enlarged head 56 whereon is formed a plurality of helical threads. The lower end of this coupling tube terminates short of the corresponding end of the axial passageway. This head 56 is adapted to be rotatively forced through the passageway into the terminal section of the tip, and in the process to form therein threads corresponding to its own helical threads whereby to

effect a press-fitted connection therewith. The head of the coupling tube thus engaged with the terminal section of the tip is wholly accommodated therewithin so as to lie just beyond the upper tapered section of the tip.

Within the tapered section of the tip, near its smaller end, is a keyway 60 for receiving a boss 61 that is projected radially from the coupling tube. When entered within the keyway, the boss is advanced to the inner end thereof into abutting relation therewith. The tapered tip section is accordingly locked non-rotatably to the coupling tube. The coupling and tapered section of the tip are rotatable together during the operation of press-fitting the tube head 56 into the terminal section 59 of the tip. Thereafter the two sections of the tip remain inseparably and immovably connected through the medium of the coupling tube.

I provide in the coupling tube one or more longitudinal slits 65 which may be confined to the region adjacent the nose 40 in the lower end of the body. Between these slits the walls of the tube are bowed outwardly (see Fig. 2) in the form of spring sections which are adapted to engage resiliently with the surrounding walls of the body nose. A frictional, yet separable, connection is thereby provided between the body and tip through the medium of the coupling tube.

Mounted within the coupling tube so as to extend for the full length thereof and beyond, is a lead guide tube 70 which, as shown in Figs. 1 and 2, may consist of a flat metallic ribbon which is rolled into tubular form with an intervening helical slot 71 which is continuous from end to end. The lower end of this guide tube 70 projects beyond the corresponding end of the coupling tube 55 so as to be accommodated within the bottom end of the axial passageway. The opposite end of the guide tube which remains protruded beyond the coupling tube may be knurled at 72 to facilitate its manual operation whenever the tube is to be assembled or disassembled relative to the coupling tube 55. For assembly, the lead guide tube 70 is advanced inwardly to the point of positioning a boss 74, which extends laterally therefrom near its upper end, within the reversely extending tail end 75 of a bayonet slot 76 which is formed at the upper end of the coupling tube 55. In reaching this position, the lower end of the guide tube is required to abut an annular shoulder 77 at the lower end of the axial passageway; the guide tube is then compressed toward the tip so as to advance its boss 74 into and within the bayonet slot 76, and is then rotated sufficiently to shift the boss laterally into the tail end thereof. When so positioned, the guide tube, then slightly under compression, will remain fixedly and immovably assembled with the coupling tube so as to be handled as a unit therewith. Normally the one is not separable from the other, but in the event of any clogging within the guide tube, the latter may be removed from the coupling tube to facilitate a cleaning out operation, or replacement, or repair, according to the condition that exists.

Formed for cooperation with the guide tube is a propeller 80 which may comprise a relatively inflexible wire having at its trailing end a flattened head 81, and near its leading end a tooth 82 which may be extended helically around the wire for perhaps 360°. This tooth is adapted to enter the helical slot 71 of the guide tube and, when rotated relative thereto, to induce a longitudinal travel of the propeller therewithin. The

flattened head of the propeller is received within the axial chamber c of the body. This chamber is of non-round cross section, being formed with one or more longitudinal grooves 83 (see Fig. 7) wherein the propeller head 81 is freely slidable while held against rotation.

The annular magazine m between the inner and outer body walls 35 and 36 is adapted to accommodate reserve leads l (see Fig. 6) which may be admitted thereto or withdrawn therefrom only when the eraser unit e is removed from the upper end of the pencil. By this arrangement, I provide a sufficient space, readily accessible yet normally closed off, for a supply of reserve leads which will enable the user of the pencil to employ it continuously over an extended period of time.

It will be obvious that the propelling unit which I have described serves certain very useful and manifold purposes. The two sections of the tip are interconnected by the coupling tube of the unit which also provides a frictional, yet removable, connection between the tip and body permitting the one to be rotated relative to the other. Also, by the special means by which the lead guide tube is locked within the coupling tube, the former is maintained in a state of compression, so as to remain immovable longitudinally while operating to advance the propeller lengthwise of itself, thereby to push the active lead l into writing position.

Coming now to Figs. 8-11, this form of pencil utilizes a body A and a tip B which is fitted thereto for rotation thereupon. In this case the body is chambered to receive a tube 85 having a non-round cross-sectional form, as best shown in Fig. 11, which may provide opposed grooves 86 within opposite ones of which is slidably received the flattened head 87 of a wire propeller 88. This tube is supported throughout its lower end region by the body walls which are extended inwardly to establish engagement therewith.

The propelling unit comprises a metallic tip 99 which is suitably tapered to cooperate with the tapered lower end of the body with which it engages, the extremity of the tip being slotted longitudinally at 91 in a plurality of places to provide spring jaws between which the active lead l is frictionally gripped. This tip is provided with an axial passageway wherein is an annular shoulder 95, this passageway for a distance being of uniform diameter so that its walls may engage a head 96 at the lower end of a coupling tube 97 when fitted thereto. This tube may be rotatively press-fitted to its final position of rest against the shoulder 95, and in so doing the helical threads which project from its head 96 will form in the surrounding walls of the tip like threads which coact to provide a fixed and inseparable connection between these parts.

The coupling tube is also slotted lengthwise as at 100 at one or more places to provide a plurality of resilient sections which are normally bowed outwardly (see Fig. 9). When the tip, together with its assembled coupling tube, is fitted to the end of the pencil body, these bowed spring sections engage frictionally with the tube 85, and in so doing are flattened somewhat (see Fig. 8), thereby acting to provide the desired degree of friction for maintaining these parts against normal separation while permitting free rotation of one relative to the other.

With a tip having a coupling tube of the kind described, I associate a lead guide tube here shown as an open wire coil 102 from which is

projected, near its lower end, a boss 103 and a second boss 104 near its upper end. The lower boss is adapted to be sprung outwardly into a slot 105 which is formed transversely of the coupling tube and, when fitted therewithin, will hold that end of the guide tube fixedly with respect to the supporting tube within which it is accommodated. The boss 104 near the upper end is adapted to enter a bayonet slot 106 at the upper end of the coupling tube 97 and, in response to compression of the coil tube to advance longitudinally, then laterally, thereof into a reversely turned tail end as shown in Fig. 9. The guide tube is thus maintained slightly under compression so long as its assembly with the coupling tube continues, and relative movement between the two tubes is effectively prevented in consequence.

The propeller 88 is formed with a helical tooth 108 adapted to travel between the coils of the guide tube, and in so doing to advance the propeller endwise of itself. This motion is imparted whenever the tip is rotated relative to the body, the latter then holding the propeller against rotation. By this simple form of mechanism the active lead *l* is driven forwardly so that successive portions of its extremity may be exposed for writing beyond the tip end of the pencil.

In Figs. 12 and 13 I have shown a slightly modified form of propelling unit in which the tip B comprises a tapered section 110, desirably of a composition material, and a terminal section 111 of metal having slits 112 at its extremity to provide spring jaws between which an active lead *l* may be frictionally gripped. In this construction, the axial passageway through the metallic section of the tip is interiorly threaded at 115 to engage with the threaded lower end of a metallic coupling tube 117 when fitted therewith. This passageway continues through the tapered section 110 where radially opposite slots 118 end in shoulders 119 at the lower end. The coupling tube 117 is provided with a pair of oppositely extending wings 120 adapted to enter into the slots 118 and rest against the shoulders 119 at the lower ends thereof. By reason of this interengagement, the coupling tube 117 is locked against rotation relative to the tapered section 110 so that the latter, when rotated relative to the terminal section 111, will cause the coupling tube 117 to be rotatively advanced to its final position relative thereto. In this way the two tip sections may be tightly secured together through the instrumentality of the coupling tube 117.

At its upper end the coupling tube is constricted to provide a neck 125 which is interiorly threaded for cooperation with the external threads 126 of a wire propeller 127 having a flattened head 128 near its upper end. This head is adapted to be held non-rotatably, yet slidably, within a pencil body having a non-round axial chamber with one or more longitudinal grooves of the general kind already described in connection with Figs. 7-11. Manifestly rotation of the propelling unit relative to the body will cause the propeller to be advanced lengthwise of itself whereby to push an active lead *l* outwardly as far as desired.

In Figs. 14 and 15 I have shown a still further modification of the propelling unit which comprises a one-piece tip 130, desirably of metal, with longitudinal slits 131 at its extremity to define spring jaws between which an active lead *l* may be advanced. In this case the coupling tube 135 is provided near its lower end with a slightly enlarged head 136 having helical threads of high

pitch adapted, in response to a forced rotative advance of the tube, to cut grooves in the surrounding cylindrical walls of the tip, thereby to secure the one immovably to the other. The lower end of this coupling tube stops short of the end of the passageway which is extended axially through the tip, as shown in Fig. 14.

The upper end of the coupling tube is adapted to receive therein the inset walls 140 of a sleeve 10 having a shoulder 141 adapted to abut the upper end of the tube when assembled therewith. This sleeve is formed at its lower end with a relatively wide but shallow helical groove 145, extending circumferentially for one or more turns, for receiving therein an interrupted internal thread 146 (see Fig. 15) which is projected inwardly from the surrounding coupling tube. By this thread and groove interengagement the sleeve may be advanced rotatively to its final position which is shown in Fig. 14, the sleeve then serving as an extension of the coupling tube. The outer end of the sleeve is desirably knurled at 148 to facilitate these manual operations.

Extending within the coupling tube and the sleeve walls 140 is a lead guide tube 150 here shown as a wire formed into coils which are spaced from each other to provide therebetween a continuous helical slot. The lower end of this wire coil extends beyond the corresponding end of the coupling tube so as to abut against the tapering lower end of the axial passageway of the tip. Throughout the length of the coupling tube, the fit of the wire coil therewithin is free and loose; but therebeyond, the interior diameter of the sleeve is slightly less so as to effect a frictional engagement with the wire coils at this point. Manifestly, in assembling the coil tube in place, it may be stretched, if necessary, to reduce its diameter at the upper end so as to facilitate its insertion into the sleeve extension; when allowed to resume its normal state the tube will contract somewhat thereby expanding its coils to effect a tight engagement with the sleeve. In this manner I provide for a resilient connection which is normally inseparable and immovable between the guide tube and the coupling tube through the medium of its sleeve extension, but one which permits of disassembly, if desired, for purposes of replacement, repair, or otherwise.

The propelling unit is completed by a wire propeller 155 having a flattened head 156 which is adapted to cooperate with one or more longitudinal grooves in the pencil body, as per a construction such as is shown in Figs. 7 and 11. The coupling tube 135 may also be slotted as at 158 for a limited distance lengthwise of itself in the region where it first enters the pencil body so as to engage frictionally therewith. In this manner the tip is connected to the body with capacity for rotation relative thereto. When so assembled, the propeller is restrained from rotary movement but may be advanced longitudinally, in response to turning of the tip relative to the body, whereby to propel ahead of itself the active lead *l* that is projected through the spring jaws at the extremity of the tip.

A feature of importance to my improved propelling unit is the resilient separable interfit of the coupling and guide tubes. The protruding upper end of the guide tube is readily manipulatable to effect the disassembly operation. Also the utilization of a coupling tube for fixedly interconnecting two parts of a tip in endwise relation is a further feature of importance. Such a con-

nection involves no extra parts or operations—it requires only that the coupling tube be rotatively advanced to its final position. In this operation there is formed in one of the tip sections the helical threads needed for coaction with the tube in order to establish what I have termed a press fit connection therebetween. For all practical purposes such a connection is permanent and inseparable, as it should be. There is the further advantage, from an assembly and operating standpoint, that this fixed connection between the coupling tube and one tip part establishes also a fixed and relatively inseparable connection between the two tip parts so that, in effect, they become a single unit. Here again I have simplified and economized upon the procedure necessary for assembly and interconnection of these parts which are comprised in the propelling unit.

I claim:

1. For use with a pencil having a body wherein is a non-round axial chamber open upon one end, a propelling unit comprising a tapered tip applicable to the open end of the body, a coupling tube affixed at one end to the tip and extended axially therefrom into the body chamber for frictional, yet separable, engagement therewith, the tip and tube being formed with axial passageways in communication with each other and with the axial chamber in the body, a lead guide tube fitted within the coupling tube and having one end abutting the tip and the other end protruded beyond the proximate end of the coupling tube, coacting means on the lead guide tube and on the coupling tube at its end remote from the tip for connecting the two tubes fixedly, yet releasably, one to the other, and a propeller in slideable, non-rotatable, engagement with the pencil body extended within the lead guide tube and in screw threaded connection therewith adapted to be advanced therewithin in response to rotary movement of the tip relative to the body.

2. For use with a pencil having a body wherein is a non-round axial chamber open upon one end, a propelling unit comprising a tapered tip applicable to the open end of the body, a coupling tube affixed at one end to the tip and extended axially therefrom into the body chamber for frictional and rotatable engagement therewith, the tip and tube being formed with axial passageways in communication with each other and with the axial chamber in the body, a lead guide tube fitted within the coupling tube and having one end abutting the tip, coacting means on the lead guide tube and on the coupling tube at its end remote from the tip for connecting the two tubes fixedly and releasably one to the other, and a propeller in slideable, non-rotatable, engagement with the pencil body extended within the lead guide tube and in screw threaded connection therewith adapted to be advanced therewithin in response to rotary movement of the tip relative to the body.

3. For use with a pencil having a body wherein is a non-round axial chamber open upon one end, a propelling unit applicable to the open end of the body and comprising a tip of two parts arranged end to end and formed therethrough with an axial passageway communicating with the chamber in the body, and a coupling tube fitted in the passageway of the two tip parts in threaded engagement with the outer part and in abutting engagement with the inner part and extending therefrom into the axial chamber of the body for frictional connection therewith, the coupling tube thus serving to fixedly, yet separably, unite

the two parts of the tip and to rotatably and releasably secure the tip to the body.

4. For use with a pencil having a body wherein is a non-round axial chamber open upon one end, a propelling unit applicable to the open end of the body and comprising a tip of two parts arranged end to end and formed therethrough with an axial passageway communicating with the chamber in the body, and a coupling tube fitted in the passageway of the two tip parts in threaded engagement with one and abutting engagement with the other and extending therefrom into the two parts of the tip and to rotatably, yet separably, secure the tip to the body.

5. For use with a pencil having a body wherein is a non-round axial chamber open upon one end, a propelling unit applicable to the open end of the body and comprising a tip, a coupling tube affixed at one end to the tip and extending axially therefrom into the body chamber for frictional and rotatable connection therewith, an endwise compressible lead guide tube fitted within the coupling tube and releasably locked thereto under compression, and a propeller in screw threaded engagement with the lead guide tube and movable longitudinally therewithin in response to rotation of the tip relative to the body.

6. For use with a pencil having a body wherein is a non-round axial chamber open upon one end, a propelling unit applicable to the open end of the body and comprising a tip, a coupling tube affixed at one end to the tip and extending axially therefrom into the body chamber for frictional and rotatable connection therewith, an axially compressible lead guide tube fitted into the coupling tube and connected therewith while maintained under compression, and a propeller in screw threaded engagement with the lead guide tube and movable longitudinally therewithin in response to rotation of the tip relative to the body.

7. For use with a pencil having a chambered body open upon one end, a propelling unit attachable to the open end of the body and comprising a tip of two parts in end to end relation having an axial passageway therethrough, a coupling tube fitted into the tip passageway and extended axially therefrom into the body chamber, raised helical threads on the tube adapted, in response to a forward rotation, to cut like threads in one tube part to establish a fixed connection therewith, and means on the tube in thrust engagement with the other tube part adapted to maintain the same tightly against the first tube part in unitary relation therewith.

8. A pencil in which is combined an axially chambered body and a tip, one rotatable relative to the other, a pair of tubes one axially compressible and inside the other and separably connected thereto while under endwise tension for concurrent rotation, a rotative pressed fit connection between the outer tube and the tip, and a propeller movable lengthwise through the inner tube in screw threaded connection therewith and in non-rotatable sliding connection with the body.

9. A pencil in which is combined an axially chambered body and a tip, one rotatable relative to the other, a coupling tube in fixed connection at one end with the tip and having an outwardly bowed resilient portion in frictional connection with the body chamber, an endwise compressible lead guide tube within the coupling tube extended outwardly beyond the upper end thereof, means providing a releasable lock between the

two tubes operable by rotative and axial manipulation of the outwardly extended end of the lead guide tube, and a propeller movable through the lead guide tube in screw threaded connection therewith and in non-rotatable sliding connection with the body.

10. A pencil in which is combined an axially chambered body and a tip therefor, a coupling tube connecting the tip to the body for rotation relative thereto, and a propelling mechanism comprising an axially compressible lead guide tube fitted within the coupling tube and extended outwardly beyond the upper end thereof, and a boss and bayonet slot connection between the two tubes for securing them together in unitary relation.

11. A pencil in which is combined an axially chambered body and a tip therefor, a coupling tube connecting the tip to the body for rotation relative thereto, and a propelling mechanism comprising an axially compressible lead guide tube fitted within the coupling tube and extended outwardly beyond the upper end thereof, and a screw-threaded connection between the two tubes for securing them together in unitary relation.

12. A pencil in which is combined an axially chambered body and a tip therefor, a coupling tube frictionally connecting the tip to the body for rotation relative thereto, and a propelling mechanism comprising a lead guide tube fitted loosely within the coupling tube and extended outwardly beyond the upper end thereof, and a screw-threaded connection between the two tubes for securing them together in unitary relation.

13. A pencil in which is combined an axially chambered body and a tip therefor, a coupling tube frictionally connecting the tip to the body for rotation relative thereto, and a propelling mechanism comprising a lead guide tube fitted loosely within the coupling tube and extended outwardly beyond the upper end thereof, and means affixed to the upper end of the coupling tube and in engagement with the lead guide tube to confine the latter in a fixed position axially of the coupling tube.

14. A pencil in which is combined an axially chambered body and a tip therefor, a coupling tube frictionally connecting the tip to the body for rotation relative thereto, and a propelling mechanism comprising a lead guide tube fitted loosely within the coupling tube and extended outwardly beyond the upper end thereof, and a sleeve in screw threaded connection with the coupling tube forming an extension therefor at its upper end and provided with means projecting inwardly thereof in engagement with the lead guide tube for confining the latter in a fixed position axially of the coupling tube.

15. For use with a pencil having a body wherein is a non-round axial chamber open upon one end, a propelling unit applicable to the open end of the body and comprising a tip of two parts arranged end to end and formed therethrough with an axial passageway communicating with the chamber in the body, a coupling tube fitted in the passageway of the two tip parts in threaded engagement with the outer part, there being a slot extended radially outwardly from the axial passageway of the inner tip part and extending longitudinally toward its opposite end, a wing extended outwardly from the coupling tube in position to enter the radial slot of the inner tip end and engage with the outer end of the slot to limit the axial advance of the coupling tube within the tip, the coupling tube thus serving to fixedly, yet separably, unite the two parts of the tip and to rotatably and releasably secure the tip to the body.
